UNITED STATES PATENT OFFICE.

PAUL M. RAINES, OF WEST HOBOKEN, NEW JERSEY, ASSIGNOR TO WESTERN ELECTRIC COMPANY, INCORPORATED, OF NEW YORK, N. Y., A CORPORATION OF NEW YORK.

TELEGRAPH SYSTEM.

1,407,042.

Specification of Letters Patent. Patented Feb. 21, 1922.

Application filed July 19, 1917. Serial No. 181,573.

To all whom it may concern:

Be it known that I, PAUL M. RAINES, a citizen of the United States, residing at West Hoboken, in the county of Hudson and State of New Jersey, have invented certain new and useful Improvements in Telegraph Systems, of which the following is a full, clear, concise, and exact description.

This invention relates to telegraph systems.

An object of this invention is to provide a system whereby a plurality of telegraph messages originating at separate stations may be transmitted over a plurality of branch lines or extension circuits to a main station, where they are automatically and simultaneously transferred to a main line circuit for transmission thereover, and vice versa.

Another object is to provide a system which is efficient and reliable.

In carrying out this invention there is provided distributor means and electroresponsive switching means, coordinated with a plurality of line circuits in such a manner that predetermined storing or holding and repeating of telegraphic message impulses on a two-way service basis may be automatically performed with respect to the line circuits.

This invention is illustrated in the accompanying drawing, in which Fig. 1 is a combined perspective and diagrammatic illustration of a telegraphic equipment suitable for a main station; while Fig. 2 similarly illustrates telegraphic equipment suitable for a branch or substation. In order to simplify the drawing it has been prepared to include only so much of a telegraphic equipment as will be necessary to a clear understanding of the present invention.

The service features of the present system provide that incoming message impulses from a duplexed main line conductor 5 (Fig. 1) may automatically affect a group of selecting magnets K (Fig. 2) to establish action of instrumentalities (not shown), whereby such impulses result in a printed message. Furthermore the effect of predetermined combinations of impulses prepared at a group of transmitting contacts L may at the same time be delivered to the main line conductor 5 and in turn establish a printed record at a distant station (not shown).

For convenience the embodiment chosen for illustrating the features of the present invention has been planned on the basis of a so-called five-unit code, that is, the selection of each character or other operation necessary to the printing of a message is effected through various polarity combinations or permutations of five successive units of current. Accordingly, at a distributor section A, one quadrant 2 of five segments is asso-

ciated with five sequentially controlled impulse storing or repeating relays comprising a group D. In turn these relays worked by incoming impulses from the line conductor 5, first store or detain and then repeat such impulses successively through the five contacts 95 to 99 of a rack type distributor F worked by the repeated impulses, whence the impulses reach a line conductor 8 and thereover complete circuit through two 70

polarized line relays 120 and 125 at the substation (Fig. 2). In working the line relays 120 and 125, these impulses cause a second rack distributor G to be operated and through successive closings of its five contacts 95 to 99 predetermined selections are made at a group of selecting magnets K.

Such selecting of the magnets K is on the basis that positive impulses from the line conductor 5 will cause corresponding ones 80 of the magnets K to be operated, while negative impulses from the line 5 will not result in operation of these magnets. This distinction in selecting is arranged through the provision of a set of contacts 126 on the 90 negative responding line relay 125, whereby the control from this relay is limited to operating a stepping magnet 101 of the distributor G. In addition to contacts 122 for operating the distributor G the relay 120 is 95

also provided with contacts 121 whereby a source of current 123 may be included through distributor contacts 95 to 99 to operate the magnets of group K. Impulses that result in the operation of selecting devices are usually termed marking impulses, while impulses that do not so result are termed spacing impulses. Therefore, as arranged in the present system, positive impulses correspond with marking impulses 105 while negative impulses serve as spacing impulses.

In transmitting messages from the substation (Fig. 2) various switching combinations may be prepared on five contacts L 110

- and through the operation of the distributor G, the five contacts 90 to 94 thereof successively establish these contacts L with a line conductor 9 provided to extend the circuit 5 to five corresponding contacts 90 to 94 of the distributor F, five storing or repeating relays comprising a group E, a distributor section B, thence to the main line conductor 5.
- 10 The three rotary distributors A, B and C may comprise separate units as shown, or they may be formed into a single distributor unit in which the three arms 12, 42 and 72 would be driven in unison in a counter-clockwise direction and also in synchronism with a corresponding distributor connected to the line conductor 5. Although no driving or synchronizing arrangement for the distributor is shown such equipments are 15 well known in the art.
- 15 The rack-like distributors F and G shown in perspective are substantially alike and for convenience the same reference characters have been used in designating corresponding parts in each, therefore, a brief description more particularly directed to the distributor indicated as G will suffice to convey a clear understanding of the operating features of both distributors. Accordingly, contacts 122 and 126 of the line relays 120 and 125, respectively, control the operation of a stepping magnet 101, the armature of which acts to move longitudinally a contact actuating beam 103 which carries 20 five transverse arms 104. The beam 103 is positioned aslant the contact members 90 to 100 in such a manner that as a stepping pawl 105 drops to a next lower step in a rack 107 at each forward movement of the beam 25 in response to energization of the magnet 101, successive ones of the transverse arm members 104 will come into alignment with corresponding pairs of the contact members as contacts 90 and 95, 91 and 96, etc. On 30 releasing of the magnet 101 a retractile spring 102 thrusts the beam to cause one of the arms 104 to press together its associated pair of the contacts 90 to 99. Retraction of the beam 103 also affects the stepping pawl 105 35 to move the rack 107 longitudinally in its supporting base, the holding pawl 106 thereupon drops to a next lower step of the rack and holds it against the tension of a retractile spring 108. Since the impulses that 40 45 50 55 60 65 may reach the line relays 120 and 125 are uniformly continuous, as will presently appear, the beam 103 is stepped downwardly in a rapid manner and successive pairs of the distributor contacts closed until on arriving at the lowest step the topmost one of the arms 104, on closing the contact members 94 and 99, also closes the contacts 100. The latter contacts complete a circuit from a source of current at the magnet 101, the winding of this magnet, conductor 128, con-
- tacts 100, conductor 133, contacts 141 of a relay 140, thence jointly through the winding of this relay and the winding of a relay 135, continuing thereafter through the winding of a relay 147 to an earth connection. Operation of the relay 135 establishes through its contacts 136 a holding circuit for the stepping magnet 101, and through its contacts 137 establishes an operating and holding circuit for a restoring magnet 110. In operating, the outstanding end of the armature 111 of the magnet 110 lifts the holding pawl 106 and the beam 103 resting thereon to their uppermost position in which they are shown in the drawing, following which the rack 107 is retracted by the spring 108. Operation of the relay 140 establishes a locking circuit from a current source 144 by way of contacts 143 and its contacts 142 whereby holding of this relay 140 and the relays 135 and 147 is effected. Contacts 148 of the relay 147 include a source of current 146 to operate a magnet 150 for service which will presently be described. By means of circuits and devices not shown the relay 140 on operating initiates a so-called printing cycle to record a character which may have been predeterminedly selected through the group of magnets K. Mechanism not shown, but active on the completion of a printing cycle, momentarily separates the contacts 143, thereby releasing the relays 140, 135 and 147, and in turn the stepping magnet 101 and the restoring magnet 110 of the distributor. Releasing of the stepping magnet 101 permits the beam 103 to be retracted and in this normal or starting position the lowermost transverse arm 104 establishes the closing of distributor contacts 90 and 95.
- 105 The transmitting contacts L are shown in a simplified manner for convenience of circuit illustration; therefore, in this system the equivalent of these contacts may preferably consist of contact devices adapted to be controlled by means of a punched or perforated tape, as well understood in the art, the tape and contact mechanism to be under such control of the magnet 150 that as each code unit or set-up of five impulses is transmitted, such set-up of the contacts will be cleared out and the tape advanced to effect predetermined selection of the contacts L for a next five-unit cycle of impulses.
- 110 The duplex equipment of the main line conductor 5 has been shown in elemental form in order to further simplify the drawing, a polarized relay 6 being interposed between the line 5 and an artificial line indicated by the characters A L. The connective point for incoming message impulses is at the armature or moving contact member of this relay while the connective point for outgoing message impulses is at the neutral point between the two coils of this re-

lay; therefore, outgoing impulses are neutralized and non-effective in the line relay 6, all of which arrangement and operations are well understood in the art. As indicated by the conventional plus and minus signs, incoming impulses of positive current move the armature of the line relay 6 to close its contacts 7, while incoming negative impulses move the armature to separate its contacts, in which position the armature is ineffective.

In order to bring out details of operation not touched upon in the foregoing general description of this invention it will be expedient to now trace a single positive impulse of incoming current from the main line 5; such impulse may be assumed to be the first impulse of a five-unit code combination. The action of an outgoing impulse of positive current which may also be assumed as a first impulse of a five-unit code combination, the movement of which is in part coincident with action of the incoming impulse, will also be traced and described.

The incoming impulse of positive current from the line 5 traverses the two serially connected windings of the line relay 6, thence over the artificial line A L to an earth connection. The armature of the relay is thereby moved to establish its contacts 7, and assuming that the trailer arm 12 of the distributor section A in its regular travel is at the same moment over as contact segment 13 a circuit will be thereby completed from the earth connection, the contacts 7 of the line relay 6, conductor 10, collector ring 11, trailer arm 12, segment 13, conductor 14, the winding of a relay 15, conductor 21, the contacts 23 of a relay 22 to a grounded current source 25. In responding the relay 15 closes its contacts 17 to establish a self-locking circuit further completed through a grounded bus conductor 16. Through the contacts 18 of the relay 15 another circuit is prepared which will be presently referred to. Leaving the incoming impulse for the present, attention will be directed to the outgoing impulse. Accordingly, let it be assumed that a prepared combination for a five-unit code of impulses has already been established by a punched tape on the contacts L, which preparation has, among other operations, closed the transmitter contacts 131, thereby including a grounded bus conductor 130 by way of the closed contacts 99 of the distributor G with a line conductor 9 which at present stands open at the contacts 87 of a relay 86.

At this stage of the operations and without extending the description to consider the remaining four incoming and four outgoing impulses of the assumed combinations, attention will be immediately referred to such instant as the trailer arm 72 of the distributor section C will have arrived over

the segment 73. This position of the trailer arm establish a circuit from a current source 70 to a collector ring 71, the trailer arm 72, the segment 73, a conductor 74, and the winding of a starting relay 75 to an earth connection. Operation of the relay 75 establishes a self-locking circuit which extends over its contacts 76, a conductor 78, the contacts 24 of the clearing-out relay 22 to a grounded current source 26. Operation 75 of the relay 75 also completes a second circuit extending from the relay 15 previously described as operated and held in a locked position. This circuit may be traced from a positively poled current source 29, a bus 80 conductor 30, contacts 18 of the relay 15, a conductor 20, contacts 95 of the distributor F, a bus conductor 73, contacts 77 of the relay 75, thence branching from a conductor 79 through one path formed by the winding 85 of a relay 86 to earth, and through another path formed by the line conductor 8 from which a second branching is formed through the left-hand winding of each line relay 120 and 125 to earth.

Returning for a moment to the relay 86, its contacts 87 now complete a circuit from the line conductor 9, already traced from the earth connection at L, which path continues over a bus conductor 69, contacts 90 of the distributor F, conductor 50, the winding of a relay 45, a bus conductor 51, contacts 53 of a restoring relay 52 to a source of grounded current 55. Operation of the relay 45 thereby effected establishes a self-locking circuit 95 through its contacts 47 by way of a grounded bus conductor 46. The contacts 48 of the relay 45 prepare an impulse circuit which will be considered presently.

Referring to the line relays 120 and 125, 105 the positive impulse of current already traced as present therein, operates the relay 120, while the relay 125 remains inert. The polarizing effect for these relays being established by current action from the source 110 123 through the right-hand winding of each relay, operation of the relay 120 establishes a circuit from the current source 123, contacts 121 of this relay, a bus conductor 124, contacts 95 of the distributor G, and the 115 winding of a selecting magnet 129 to earth. A second circuit may also be traced from the source of current at the stepping magnet 101, the winding of this magnet, conductor 127, contacts 122 of the relay 120 to 120 earth. Thereupon the magnet 101 withdraws the beam 103 to permit the contacts 90 and 95 to separate and also allow the stepping pawl 105 to lower the beam by dropping into the next lower step of the rack 125 107.

Referring now to the distributor F, contacts 88 of the relay 86, operated as described, include a source of current 89 with a bus conductor 83, thereby establishing current 130

action through the stepping magnet 101 of this distributor, whereupon the beam 103 is withdrawn to separate the contacts 90 and 95, and permit the stepping pawl 105 to drop 5 into the next lower step of the rack 107.

It will be noted that in the group D the relays and their circuit connections are typical as compared one with another; therefore it is obvious that the effect of the last four 10 impulses of the five-unit code assumed to have been received from the line 5 into these relays will successively and automatically become effective through the contacts 96 to 99 of the distributor F to reach the stepping 15 control relay 86 of the distributor F and also the line relays 120 and 125 to control the stepping of the distributor G, all as described for the first impulse. On receipt 20 of the fifth or last impulse from the relays D the beam 103 of the distributor F will be at its lowermost position and holding the contacts 94, 99 and 100 closed. Therefore, coincident with the fifth impulse and the 25 operation of the stepping relay 86 and the closing of its contacts 88 to include the current source 89 with the bus conductor 83 the contacts 100 connect this bus conductor to a conductor 84 energize the left-hand winding of a clearing-out relay 80. On operating, 30 the relay 80 establishes a self-locking circuit through its right-hand winding, its contacts 82, a conductor 78, contacts 24 of the relay 22 to the current source 26. The contacts 81 of the relay 80 establish a current source 35 85 with the bus conductor 83, thereby energizing this bus independently of the stepping relay 86, which may release immediately on cessation of the signaling impulse from the last relay in group D. In addition to 40 providing the locking circuit described, the contacts 82 of the relay 80 also establish the current source 26 to operate the distributor clearing-out magnet 110 of the distributor F. The stepping magnet 101 of this distributor, having already operated under current from the bus 83, has withdrawn the beam 103 to effect clearance of the five transverse arms 104 thereof with respect to the contact members 90 to 99. Therefore, action 45 50 of the magnet 110 lifts the holding pawl 106 and beam 103 to their first or normal position as already described.

Operation of the magnet 110 also connects a source of current 112 over contacts 113, a 55 conductor 114 and the winding of the lock-release relay 22 to earth. The relay 22 thereupon operates and by separation of its contacts 23 disconnects the current source 25 from the bus conductor 21 common to the 60 winding of each relay in the group D, thereby disconnecting all of the relays of this group. Separation of the contacts 24 of the release relay 22 disconnects the current source 24 from the several paths, namely, the 65 winding of the relay 75, the right-hand

winding of the relay 80, and the winding of the distributor restoring magnet 110. Releasing of the magnet 110 separates its contacts 113 to disconnect the relay 22, whereupon the equipment is again in its normal 70 condition except for the outgoing impulse which will presently be further described.

It will be understood that the various operations of the distributors F and G are relatively in step or time phase one with the 75 other; therefore, the releasing or restoring operations just described in connection with the distributor F of course took place coincident with the restoring operations already described in connection with the distributor G.

Referring to the relay 45 of group E, retained locked by the action of the outgoing impulse already traced to that point, let it be assumed that the trailer arm 42 85 of the distributor section B has arrived over a segment 43 of that section. This position of the arm 42 establishes a circuit from a current source 57 of positive polarity, a bus conductor 58, the contacts 48 of the relay 90 45, a conductor 44, the segment 43, the trailer arm 42, a collector ring 41, a conductor 40 to the outgoing connective point on the duplex equipment of the line conductor 5, thereby disposing of the outgoing 95 impulse.

The relays and circuit connections thereof comprising the group E are, as may be noted, typical as compared one with another, therefore, the last four impulses forming 100 the assumed five-unit code would have been duly stored successively therein following the storing of the first impulse at the relay 45. Accordingly, as the trailer arm 42 successively passes over the associated segments in the quadrant 2 of the distributor section B, impulses of current corresponding 105 in polarity with the previous selective conditioning of these relays would be released to the line conductor 5. Following 110 the release of the fifth or the last one of an impulse combination from the relays E to the line conductor 5, the trailer arms of the distributor sections will have advanced to the respective quadrant zones 3, 115 whereupon a circuit will be established at the section C which may be traced from a current source 70, the collector ring 71, the trailer arm 72, a segment 56, a conductor 54 and the winding of the relay 52 to earth. 120 Relay 52 thereby operated separates its contacts 53 to disconnect the current source 55 from the bus conductor 51 common to the winding of each relay in the group E and through this action clears out or deenergizes any of the relays in this group which may have been operated under the last 125 code cycle transmitted therefrom.

Referring further to the matter of negative impulses in this system it will be noted 130

that the normal contacts of each relay in the groups D and E, as the contacts 19 and 49 respectively of the relays 15 and 45, are established with negatively poled current sources. For the relays D this current supply is from a source 27 of negative polarity, and a bus conductor 28 while a negatively poled current source 59 and a bus conductor 60 supply the normal contacts of the relays in the group E. Although negative impulses are transmitted and received over the main line conductor 5 it will be apparent that for a transmitted impulse of negative current a corresponding one of the transmitter contacts L may remain open, since a corresponding relay in the group E may for such impulse remain inert. The same results obtain for incoming negative impulses, as under such impulses, the contacts of the line relay 6 are disabled; therefore, no circuit is completed through a corresponding one of the relays D and accordingly such relay remains inert.

Further service features of the present system provide that messages may be transmitted from the substation over the main line circuit 5 independently of or in the absence of incoming messages from this main line, and vice versa. Such independent transmitting or receiving of messages is effected through the continuous operation of the distributor sections A, B and C. From the description of the system already given and an inspection of the drawing it will be obvious that, irrespective of incoming or outgoing impulses by way of the main line 5, continuing operation of the distributors A, B and C will in turn render code cycles each comprising five negative impulses to be established from the relays of the group D. These successive negative impulses by operating the stepping control relay 86 cause the distributor F to be correspondingly worked, and the same negative impulses by operating the line relay 125 at the substation cause the distributor G at that point to be worked without causing operation of the selecting magnets K.

In the matter of service capacity of this system it may be readily extended by including other telegraphic equipments with the idle segments in the zones or quadrants 1, 3 and 4 of the distributor sections A, B and C. If desired three additional equipments, each identical with the equipment shown, may be respectively included with the three idle quadrants of the distributors, thereby increasing the capacity of the system fourfold. Such branchings or forking 60 of the quadrants 1, 2, 3 and 4 may serve that number of different substations.

What is claimed is:

1. In a telegraph system, a plurality of lines, relays for the reception and storing 65 of impulses routed in one direction, other

relays for the reception and storing of impulses routed in another direction, first, second and third distributor means, means to render impulses in one direction effective to control said third distributor means, and means jointly controlled by said distributors to render said first and second mentioned relays effective to repeat telegraphic impulses in their respective directions over said lines.

2. In a telegraph system, a plurality of lines, a plurality of impulse detaining relays, distributor means for the inclusion of impulses from said lines in a first order with said relays, further distributor means for releasing detained impulses from said relays in a second order, other distributor means controlled by impulses of one order, and means controlled by said other distributor means to jointly act with the first and second mentioned distributors in establishing 85 said impulses effective in their respective orders with said line circuits.

3. In a telegraph system, a plurality of lines, impulse storing relays, first distributor means for controlling the inclusion of impulses routed in one direction with said relays, other impulse storing relays, second distributor means for including impulses routed in another direction with said other relays, third distributor means controlled by the impulses routed in one direction, means controlled by said third distributor means to jointly act with said relays and said first and second distributor means for establishing 100 said impulses effective in their respective direction, electro-responsive means for controlling the operative condition of said relays, and other distributor means for disabling said electro-responsive means.

4. In a telegraph system, a duplexed line, a first station, a plurality of relays at said station, a distributor for including incoming impulses from said line to be stored in said relays, a second station, receiving and transmitting equipment for said second station, a first line joining said stations, distributor means for said first line at each station, means controlled by the impulses stored in said first relays for operating the last mentioned distributors, means controlled 115 by the latter distributors for establishing said stored impulses effective with the receiving means at the second station, a second plurality of impulse storing relays at said first station, a second line circuit joining said stations, distributor means for rendering stored impulses from said second plurality of relays effective with said duplexed line, and means controlled by the distributors of said first line to establish 120 impulses from said transmitting means at the second station over said second line to be stored in said second plurality of relays.

5. In a telegraph system, a duplexed line, a first station, a plurality of relays at said 130

- station, a distributor for including incoming impulses from said line to be stored in said relays, a second station, receiving and transmitting equipments for said second 5 station, a first line joining said stations, distributor means for said first line at each station, means controlled by the impulses stored in said first relays for operating the last mentioned distributors, means controlled by 10 the latter distributors for establishing said stored impulses effective with the receiving means at the second station, a second plurality of impulse storing relays at said first station, a second line circuit joining said 15 stations, distributor means for rendering impulses stored by said second plurality of relays effective with said duplexed line, means controlled by the distributors of said first line to establish impulses from said transmitting means at the second station over said 20 second line to be stored in said second plurality of relays, and other distributor means for disabling the distributors of said first line.
- 25 6. In a telegraph system, a main line, duplex equipment for said line, a second line and transmitting equipment therefor, a third line and receiving equipment therefor, a first distributor section included with the receiving point of said duplex equipment, a second distributor section included with the sending point of said duplex equipment, a first plurality of relays included with said first distributor and controlled thereby to receive 30 impulses from said main line, a second plurality of relays included with said second distributor and controlled thereby to release impulses to said main line, a third distributor included with said second and third 35 lines and respectively with the transmitting and receiving equipments thereof, a fourth distributor means included with said first relays and said third line and said second relays and said second line, and a fifth distributor for conditioning said first relays effective to operate said third and fourth distributors to render impulses from said main line effective with said receiving equipment and to render impulses from said transmitter 45 effective with said second relays.
- 50 7. In an automatic telegraph system, the combination with main line continuously operating synchronous apparatus, of extension circuit means, extending to a distant point, transmitting means in connection with such continuously operating synchronous apparatus, and comprising a restarting translator adapted to transmit through such extension circuit means characters transmitted to it through such continuously operating synchronous apparatus, receiving and recording means at such distant point comprising a restarting receiving translator adapted to receive and record characters 55 transmitted through such extension circuit
- means, transmitting means at such distant point and home receiving means comprising a receiving translator, in connection with such continuously operating synchronous apparatus, such transmitting means arranged to transmit, through the transmitting translator at such distant point, and the extension circuit means and the last mentioned receiving translator, into said continuously operating synchronous apparatus. 70 75
8. In an automatic telegraph system, the combination with a main line distributor, of extension circuit means extending to a distant point, means operated by such distributor for repeating into such extension 80 circuit means, receiving means at the distant point arranged to receive signals so repeated, transmitting means at the distant point comprising a restarting translator, such transmitting means and translator arranged to transmit through such extension circuit means, and repeating means arranged to receive signals so transmitted from the distant point and to repeat them into said main line distributor, and comprising a receiving 90 translator and means controlled thereby for setting up contact combinations corresponding to the signals received.
9. In an automatic telegraph system, the combination with a distributor comprising a 95 segmented commutator ring and a brush adapted to travel thereover, said distributor comprising also a series of relays controlled by segments of such commutator and adapted by reason of such control to set up various contact combinations corresponding to telegraph characters, of a restarting transmitting translator arranged to be started in operation by a starting pulse, and having a 100 series of contacts closed seriatim when said translator operates, each of said relays having a contact connected in series with one of said translator contacts, an extension conductor into which said transmitting translator transmits, and a receiving translator arranged to be started in operation by a starting pulse transmitted through such extension conductor, said distributor having a starting-pulse contact arranged to transmit to such translators a starting pulse, said contact arranged to be closed subsequent to the passage of such brush over the last of such relay-controlling segments of the commutator. 105 110 115
10. In an automatic telegraph system, the 120 combination with a distributor comprising a segmented commutator ring and a brush adapted to travel thereover, said distributor comprising also a series of relays controlled by segments of such commutator and adapted by reason of such control to set up various contact combinations corresponding to telegraph characters, of a restarting transmitting translator arranged to be started in operation by a starting pulse, and having a 125 130

series of contacts closed seriatim when said translator operates, each of said relays having a contact connected in series with one of said translator contacts, an extension conductor into which said transmitting translator transmits, a receiving translator arranged to be started in operation by a starting pulse transmitted through such extension conductor, said distributor having a 10 starting-pulse contact arranged to transmit into such translators a starting pulse, said contact arranged to be closed subsequent to the passage of such brush over the last of such relay-controlling segments of the commutator, and a recorder controlled by said receiving translator.

11. In an automatic telegraph system, the combination with main line continuously operating synchronous apparatus, of extension 20 circuit means, extending to a distant point, transmitting means in connection with such continuously operating synchronous apparatus, and comprising a restarting translator adapted to transmit through such extension 25 circuit means characters transmitted to it through such continuously operating synchronous apparatus, receiving and recording means at such distant point comprising a restarting receiving translator adapted to receive and record characters transmitted through such extension circuit means, transmitting means at such distant point, and home receiving means comprising a receiving translator, in connection with such continuously 30 operating synchronous apparatus, such distant transmitting means arranged to transmit, through the transmitting translator at such distant point, and the extension circuit means and the last mentioned receiving 35 translator, into said continuously operating synchronous apparatus, said continuously operating synchronous apparatus comprising means for starting the first mentioned transmitting translator and the receiving and transmitting translators at the 40 distant point.

12. In an automatic telegraph system, the combination with main line continuously operating synchronous apparatus, of extension 50 circuit means, extending to a distant point, transmitting means in connection with such continuously operating synchronous apparatus, and comprising a restarting translator adapted to transmit through such extension 55 circuit means characters transmitted to it through such continuously operating synchronous apparatus, receiving and recording means at such distant point comprising a restarting receiving translator adapted to receive and record characters transmitted through such extension circuit means, transmitting means at such distant point, and home receiving means comprising a receiving translator, in connection with such continuously 60 operating synchronous apparatus, such

distant transmitting means arranged to transmit, through the transmitting translator at such distant point, and the extension circuit means and the last mentioned receiving translator, into said continuously operating 70 synchronous apparatus, said continuously operating synchronous apparatus comprising means for starting the first mentioned transmitting translator and the receiving and transmitting translators at the 75 distant point and for determining the time of transmission into it of the characters transmitted from such distant point.

13. In an automatic telegraph system, the combination with main line continuously operating synchronous apparatus, of extension circuit means, extending to a distant point, transmitting means arranged to repeat thereinto signals received from said continuously operating synchronous apparatus, receiving means at such distant point arranged to receive signals transmitted through such extension circuit means, transmitting means at such distant point and home repeating means therefor in connection with such main line continuously operating synchronous apparatus, and adapted to be operated by the transmitting means at the distant point, and, when so operated, to transmit into such continuously operating synchronous apparatus, said continuously operating synchronous apparatus comprising means for starting the receiving means and the transmitting means at the distant point, and for determining the time of transmission 100 into it by the said home repeating means, both said transmitting means being non-synchronous with respect to said continuously operating synchronous apparatus.

14. In a telegraph system, the combination 105 of a restarting transmitting translator having contacts closed seriatim in each cycle of operation of such translator and an automatic transmitter having contacts connected severally with corresponding contacts of 110 said translator and having a clearing magnet which when energized clears the said transmitter contacts, and means operated by said translator for energizing said magnet at the conclusion of a cycle of operations of said 115 translator.

15. In a telegraph system, a plurality of stations, a multiplex synchronous system connecting two of said stations, a start-stop system extending from one of said stations 120 to a distant station, means for transmitting code combinations of message impulses over said multiplex system, means for automatically transferring said message impulses from said multiplex system to said start-stop 125 system, and means at said distant station for recording said impulses.

16. In a telegraph system, a plurality of stations, a multiplex synchronous system connecting two of said stations, a start-stop 130

- system extending from one of said stations to a distant station, means for transmitting code combinations of message impulses over said start-stop system, and means for automatically transferring said message impulses from said start-stop system to said multiplex system.
17. In a telegraph system, a plurality of stations, a multiplex synchronous system connecting two of said stations, a start-stop system extending from one of said stations to a distant station, means for transmitting message impulses over said multiplex system, means for transmitting message impulses over said start-stop system, and means for simultaneously transferring message impulses from said multiplex system to said start-stop system and from said start-stop system to said multiplex system.
18. In a telegraph system, a sunflower device, means to operate said sunflower device uniformly, a series of relays, an electrical connection between the coils of said relays and said sunflower device, a transmitting device started into operation at the beginning of each signal and automatically stopped at the end of each signal, said transmitting device including a series of transmitting contacts, said contacts being individually connected to the contacts of corresponding ones of said relays so that said relays control the character of the impulse transmitted by said transmitting contacts.
19. In a telegraph system, a sunflower device, means to operate said sunflower device uniformly, a series of relays, an electrical connection between the coils of said relays and said sunflower device, a transmitting device started into operation at the beginning of each signal and automatically stopped at the end of each signal, said transmitting device including a series of transmitting contacts, said contacts being individually connected to the contacts of corresponding ones of said relays so that said relays control the character of the impulse transmitted by said transmitting contacts, a control relay, means to operate said control relay when any of the relays of said series are operated, and means controlled by said control relay to start said transmitting device into operation at the beginning of a signal.

In witness whereof, I hereunto subscribe my name this 14th day of July, A. D., 1917.

PAUL M. RAINY.
